[57] CLAIM

The ornamental design for a bottle, as shown and described.

DESCRIPTION

FIG. 1 is a front perspective view of a bottle showing my new design;

FIG. 2 is a front elevational view the opposite side being substantially the same as the front;

FIG. 3 is a side elevational view; and

FIG. 4 is a side elevational view showing a modified form of my new design.

The front and rear of the modified form are plain and unornamented and the sides each have the outline shown in FIG. 2.
